UNITED STATES PATENT OFFICE.

JACOB SOKOLOV, OF NEW YORK, N. Y.

WRENCH.

1,159,428.

Specification of Letters Patent.

Patented Nov. 9, 1915.

Application filed August 6, 1914. Serial No. 855,377.

To all whom it may concern:

Be it known that I, JACOB SOKOLOV, a citizen of the United States, residing in Bronx, city of New York, State of New York, have 5 invented certain new and useful Improvements in Wrenches, of which the following is a specification.

My invention relates to wrenches, and resides more particularly in a wrench adjustable to take nuts, bolts, etc., of different sizes, means being provided for engaging and disengaging the jaw adjusting means, to the end that the adjustable jaw may be quickly moved to a new position, the adjusting means reengaged, and further adjustment procured through the usual adjusting means; and to the further end that the nut or bolt may be tightened by simply oscillating the handle, without removal of 20 the wrench from the nut or bolt.

My invention resides in a wrench of the character hereinafter described.

For an illustration of one of the forms my invention may take reference is to be had 25 to the accompanying drawings in which:

Figure 1 is a top plan view of the wrench. Fig. 2 is a side elevational view of the same. Fig. 3 is a fragmentary view, similar to Fig. 1, with the adjusting means disengaged. Fig. 4 is a sectional view through parts shown in Fig. 1, with the adjusting means in engagement. Fig. 5 is a sectional view taken on the line X—X of Fig. 1. Fig. 6 is a sectional view taken on the line 35 Y—Y of Fig. 4.

H is the handle member terminating in the parts 1 and 2 between which is the notch or space 3. The wrench head 4 has the integral jaw 5 and back of the jaw 5 the head 40 4 consists of the two cheek members 4, 4' separated by a space 6 into which extends the parts 1 and 2 of the handle member H. The head 4 is pivoted to the member 2 upon the screw or pin 7, and upon this pivot 7 the head may partake of pivotal movement, as to the position indicated in Fig. 3, for purposes hereinafter stated. In the transverse channel or opening 8 in the head 4 is slidable the bar 9 with which the movable 45 50 jaw 10 is integral, the sides of the jaw 10 being roughened by ribs 11 or otherwise to afford a suitable grip for the hand or fingers. On its inner edge the bar 9 has worm or rack teeth 12 adapted to engage with the

screw thread or worm 13 on the member 14 55 rotatable upon the pin 15 having bearings in the members 16 on the member 17, the members 16 being more or less resilient and pressing against the ends of the member 14 to cause sufficient friction to prevent the 60 member 14 from easily rotating. In the member 17 is a notch 18 into which freely extends the pin 19 extending at right angles to the plane of the member 20 pivoted to the handle H on the pin or screw 21. 65 Through the wing or member 1 on handle H is a perforation having a circular end 22 and a square end 23 as shown in Fig. 4. In the cheeks 4, 4' of the head 4 are circular openings 24 and 25 into which extends the 70 rotary locking member or pin 26, half of the pin 26 being cut away at its middle where it extends through the member 1, such pin 26 having the section at this point shown at 75 27 in Fig. 4. At its larger end the pin 26 has a rib or other means 28 by which the pin may be turned.

As seen in Figs. 4 and 6, the member 9 has a hole or longitudinal slot 29 in which is disposed a helical spring 30 whose one 80 end abuts against the member 9 and whose other end abuts against the member 31 held by screw 32 to the head 4, the member 31 having a pin 33 extending into the spring 30. With the parts in position the spring 85 30 opposes the movement of jaw 10 away from jaw 5.

The operation is as follows: The pin 26 is rotated a half revolution from the position shown in Figs. 4 and 5 in which position the notch 27 will allow the head 4 to rotate in a counter-clockwise direction upon its pivot 7, as viewed in Figs. 1, 3 and 4 because the edge 23 of the member 1 can enter such notch. The head so rotated is 90 shown in Fig. 3, and in this position the worm 13 is disengaged from the teeth 12, and the operator may then pull the jaw 10 downwardly, as viewed in Figs. 1, 3 and 4, in opposition to spring 30, to allow placing 100 the jaws 10 and 5 upon a nut or bolt. When the operator releases the jaw 10 the spring 30 will move it against the nut or bolt. Then the nut or bolt may be turned by moving the handle H downwardly, and in so 105 doing will restore the head to the positions indicated in Figs. 1 and 3. If the parts should not take this position of Figs. 1 and

3 due to engagement of the worm 13 on the top edge of the teeth 12, the worm 13 may be slightly rotated until complete mesh occurs. Continuing downward movement on 5 the handle H will turn the nut or bolt. In moving the handle H upwardly the head will again swing upon its pivot 7, and the jaw 10 being disengaged from the worm 13, the jaw 10 will ride over an angle of the 10 nut or bolt and engage upon the next side of the nut or bolt, whereupon the handle H may be moved downwardly again to further rotate the nut or bolt. And so on in successive movements the head will rotate upon 15 its pivot 7, disengage the adjusting means, and again reengage it and turn the nut or bolt. This action makes it unnecessary to lift the wrench from the nut or bolt to place it upon a new face, it only being necessary 20 to oscillate the handle H backwardly and forwardly through an angular distance equal to the difference in angles between the faces of the nut or bolt. If, however, it is desired to convert the wrench into a so 25 called solid wrench, the pin 26 is turned to the position shown in Fig. 4 with the worm 13 in mesh with the teeth 12. With the parts so locked rotation of the member 14 will adjust the jaw 10 in the well known 30 manner.

What I claim is:

1. In a wrench, a handle member, a head member movable thereon and carrying a fixed jaw, an adjustable jaw on said head, 35 means carried by and movable with respect to said handle member for engaging said second jaw, movement of said means while in engagement with said second jaw adjusting the same on said head, movement of said 40 head upon said handle in one direction disengaging said adjusting means from said second jaw.

2. In a wrench, a handle member, a head member movable thereon and carrying a 45 fixed jaw, an adjustable jaw on said head, means carried by said handle member for adjusting said second jaw, movement of said head upon said handle in one direction disengaging said adjusting means from said 50 second jaw, and resilient means on said head opposing opening movement of said second jaw.

3. In a wrench, a handle member, a head member movable thereon and carrying a 55 fixed jaw, an adjustable jaw on said head, means carried by and movable with respect to said handle member for adjusting said second jaw, movement of said head upon said handle in one direction disengaging 60 said adjusting means from said second jaw, and means for locking said head in fixed position upon said handle member with said adjusting means in engagement with said second jaw.

4. In a wrench, a handle member, a head 65 member movable thereon and carrying a fixed jaw, an adjustable jaw on said head, rotatable means carried by said handle member for adjusting said second jaw, movement of said head upon said handle in one 70 direction disengaging said adjusting means from said second jaw, and a member on which said adjusting means rotate pivoted to said handle member.

5. In a wrench, a handle member, a head 75 member pivoted thereon and carrying a fixed jaw, a second jaw adjustable on said head member, a rack on said second jaw, a rotatable member carried by said handle member meshing with said rack for adjusting said second jaw, movement of said head member upon said handle member in one direction disengaging said rotatable member from said second jaw.

6. In a wrench, a handle member, a head 85 member pivoted thereon and carrying a fixed jaw, a second jaw adjustable on said head member, a rack on said second jaw, a rotatable member carried by said handle member meshing with said rack for adjusting said second jaw, movement of said head member upon said handle member in one 90 direction disengaging said rotatable member from said second jaw and in opposite direction reengaging said second jaw and locking 95 the same against movement away from said fixed jaw.

7. In a wrench, a handle member, a head member pivoted thereon and carrying a fixed jaw, a second jaw adjustable on said 100 head member, a rack on said second jaw, a rotatable member carried by said handle member meshing with said rack for adjusting said second jaw, movement of said head member upon said handle member in one 105 direction disengaging said rotatable member from said second jaw, and a member on which said rotatable member is supported pivoted to said handle member.

8. In a wrench, a handle member, a head 110 member pivoted thereon and carrying a fixed jaw, a second jaw adjustable on said head member, a rack on said second jaw, a rotatable member carried by said handle member meshing with said rack for adjusting 115 said second jaw, movement of said head member upon said handle member in one direction disengaging said rotatable member from said second jaw, and means extending through said head and handle members 120 for locking said head on said handle when said rotatable member and said rack are in mesh.

9. In a wrench, a handle member, a head member pivoted thereon and carrying a 125 fixed jaw, a second jaw adjustable on said head member, a rack on said second jaw, a rotatable member carried by said handle

member meshing with said rack for adjusting said second jaw, movement of said head member upon said handle member in one direction disengaging said rotatable member 5 from said second jaw, and resilient means opposing separation of said jaws.

In testimony whereof I have hereunto af-

fixed my signature in the presence of the two subscribing witnesses.

JACOB SOKOLOV.
